UNITED STATES PATENT OFFICE.

WALTER ARTHUR BROWN, OF LOS ANGELES, CALIFORNIA.

PROCESS OF SEPARATING AND TOPPING HYDROCARBONS FROM A WATER MIXTURE.

1,419,610.

Specification of Letters Patent. Patented June 13, 1922.

Application filed February 24, 1919. Serial No. 278,727.

To all whom it may concern:

Be it known that I, WALTER ARTHUR BROWN, a citizen of the United States, residing at Los Angeles, in the county of Los Angeles, State of California, have invented new and useful Improvements in Processes of Separating and Topping Hydrocarbons from a Water Mixture, of which the following is a specification.

10 This invention relates to such processes as I have set forth in my Patent No. 1,309,794, granted July 15, 1919; and this invention relates more particularly to a process in which topping of the hydrocarbons, such as petroleum oils, is carried on simultaneously with the separation of the water and oil from a mixture thereof.

I have set forth in said patent a process particularly applicable to separating hydrocarbons and water from an emulsion mixture. I have now devised an additional step for such a process by which a topping, or a partial topping, of the petroleum oils may be effected at the same time that the separation is taking place without any loss of time.

The process described in said patent and that which I herein describe, may be carried out in any suitable apparatus of which I show a typical form in the accompanying drawing in which—

Fig. 1 is a diagram showing in longitudinal section a treating tank and a condenser, and Fig. 2 is a diagram showing a cross-section of a treating tank.

35 In these views I show a tank 10 which may preferably be a cylindrical tank laid substantially horizontally. This tank is provided with a plurality of steam heating coils, which may be of any suitable number. In

40 the actual practice of this process as I now carry it out, I use a tank with three superimposed coils; but for certain purposes, as will be hereinafter described, it may be desirable to have a tank having a larger number

45 of superimposed coils. Such an arrangement is shown at 11^a, 11^b, 11^c, 11^d and 11^e. The tank may be provided with any suitable valve controlled inlet, as shown at 12, and valve controlled outlet, as shown at 13 at the

50 bottom of the tank. And in addition there may be other outlets higher up on the tank, as is indicated at the valve controlled outlet 14. This upper outlet may be for the purpose of simultaneously withdrawing the oil

55 from the upper part of the tank while water is being withdrawn from the lower part of

the tank. The tank is also provided with a pressure gauge 15, a thermometer 16, and test cocks at 17. A vapor outlet may be provided at 18 and this may be controlled by an 60 adjustable pressure valve which will open when a certain pressure is reached; or, as will be readily understood, the outlet may be controlled by a hand valve without any automatic opening features. The vapor pipe 65 19 may lead to a condenser 20 of any usual form.

In the normal practicing of my dehydration process, as set forth in said prior patent, the tank is filled close to its top with the 70 oil and water mixture and the whole body of liquid is then heated up to a temperature somewhere around or somewhat above the normal boiling point of water; and at the same time the petroleum vapors and the 75 small amount of water vapor which are generated are released through the vapor line, the valve being set to hold just enough pressure to prevent free vaporization of water at the temperature employed. This 80 condition is held upon the liquid until it is found by tests that the emulsion mixture has been broken down and that the water is then separable from the oil. The next step is then to settle the water; and usually, in 85 order to accelerate the coalescence of the water particles and the settling of the water to the bottom of the tank, I increase the pressure with relation to the temperature.

That is, I may either actually increase the pressure upon the surface of the liquids without making any substantial change in the temperature of the whole body of the liquid, or I may allow the temperature of the whole body of liquid to decrease without decreasing the pressure upon the surface of the liquid; or I may do both these things together. This relative increase in pressure may be effected in many ways, so far as the carrying on of the dehydration process alone 90 is concerned. For instance, this may be effected by turning in steam or air pressure over the surface of the liquid, either to maintain the previous pressure while allowing the temperature of the body of liquid to fall, or to increase the previous pressure while maintaining the temperature of the body of liquids at, or substantially at the previous temperature. As a matter of actual practice it is usually the fact that the temperature of the body of liquid falls somewhat 95 and I also actually raise the pressure, the

temperature falling by radiation loss of heat, unless steam is put through the steam heating coils in sufficient quantity to balance the loss.

5 But I may effect this relative increase of pressure by heating the upper part of the body of liquid without heating the lower part of the body of liquid, the liquid being relatively slow of circulation and a relatively poor conductor of heat. By turning steam in sufficient quantity and of proper temperature through the upper coil or upper coils, I can heat the upper layer of liquid and thereby generate some additional 10 pressure by vaporization of the lighter oil constituents, while the temperature of the remainder and larger portion of the body of liquid remains constant or perhaps falls somewhat. The general object of this relative increase in pressure is to stop further generation of vapors from the whole body of the liquid and therefore to stop the agitation due to that vaporization and to hold the whole body of liquid quiescent during 15 the settling of the water, thus allowing the water, which has been reduced from its emulsion combination, to settle readily and freely. But it will be apparent that it is the top layer of the liquid which becomes 20 freed of water first by the settling of the water; and furthermore, the generation of a small amount of vapor in the top layer does not agitate the main body of the liquid at all and only agitates the top layer very 25 little. I have thus found that this method of increasing the pressure can be carried out without interfering with the settling of the water. Now by this method of raising the pressure, I of course generate additional oil 30 vapors. Certain vapors have been previously generated from the oil (providing the oil has constituents which vaporize at a lower temperature than water) and now by this rise of temperature of the upper portion of the liquid, I generate an additional oil vapor to make the required additional pressure; or I generate more of the same kind of vapors that have been generated before, in order to maintain the pressure 35 sure that has been held before, while the temperature of the lower parts of the liquid falls. In either case it will be seen that certain additional vapors are generated from the upper layer of the liquid, which upper layer is at first a mixture of oil and water but quickly becomes practically pure oil. Thus I am enabled to at least partially and sometimes wholly top the oil at the same time that the water is settling out. And this 40 is particularly true where, although not limited to such a circumstance, the proportion of oil is low as compared to that of water; that is, where the upper layer or upper part of liquid which I may heat to a higher temperature or keep at the previous tempera- 45

ture without undue agitation of the whole body of liquid, comprises the whole or most of the oil in the whole body of liquid.

As an instance of actual practice, I may cite the following: The breaking up of the emulsion may require say, a temperature of 220° F. and during the holding of this temperature upon the mixed liquids I hold a pressure on top the liquids of say, four or five pounds per square inch. Having held this pressure and temperature for a sufficient length of time to cause the emulsion to break up, which time may be from a few minutes to thirty minutes or so, or perhaps in some cases longer, I then immediately apply steam to the upper coil or coils to increase the temperature of the upper layer of the liquid. At the same time the outlet valve is arranged to then hold a higher pressure than has been previously held. Usually, in practice, I find it sufficient to increase the pressure by six to ten pounds per square inch; and the valve will be set for this increased pressure. Steam is turned through the upper layers of the liquid to raise the temperature so as to generate the increased pressure and a sufficient excess of temperature to force off oil vapors at that increased pressure. The temperature in the upper layers of the oil then depends entirely, for any given pressure held, upon the characteristics of the oil and the tops desired; but in a typical average case, where the total pressure held during that time is say, ten to fifteen pounds, the temperature which I employ may be approximately 250°-300° F. This temperature is maintained in the upper layer of the liquid, which quite soon becomes pure oil, for a length of time sufficient to fully top the oil and remove all vapors which may be generated at that temperature, and also for a length of time sufficient to allow the water to settle out. As a general rule I find that I can take off all of the vapors normally known as tops (that is, those down to about 37° B. gravity) in the length of time it requires water to settle out. Toward the last of this operation, after the water is settled completely out of the top layer, the pressure usually is allowed to fall and may almost reach atmospheric. 100

Although this particular method of procedure may be carried out more or less regardless of the proportion of oil and water in the mixture, I find it particularly efficacious where the proportion of water is high. Where the proportion of water is not so high, I may heat and generate vapors and thus top the upper layer or part of the oil; but where the proportion of water is higher, say 50 or 60% or higher, I may heat and thus generate vapors from, and top the whole of the body of oil. These statements, however, are comparative and relative rather than absolute; because even where the pro- 110

portion of oil is comparatively high and the proportion of water comparatively low, the whole of the body of oil may be heated if the heating is carried on slowly and gently 5 so as to not cause violent or fast vaporization of the lighter constituents of the oil; the temperature and pressure at all times being regulated so that, although the temperature to which the upper parts of the liquid 10 is raised is sufficient to generate hydrocarbon vapors against the increased pressure employed, it is not sufficient to generate any large amount of water vapors against the increased pressure employed. Furthermore, 15 where the proportion of oil is high and that of water low, I may first heat only the upper layer of the oil by using only the uppermost coil, and then as soon as the water settles I may turn steam into the next coil below 20 and heat the next layer of oil and so on until, when the water has finally settled out, and during the time when the water is being withdrawn from the tank, the whole of the body of oil may be heated and the desired 25 vapors taken therefrom. In heating the upper layer at any time, or any lower layer when it is practically freed of water, the temperature may be carried above that of water vapor at the pressure used; because 30 the vaporization of a small amount of water from the upper layer, or slowly from any layer, does not retard the settling action. As a matter of fact, it is usually true that 35 there is some water in any layer of oil which is thus heated and usually there is some water vapor going off with the oil vapors. And it will be particularly noted that in any case, regardless of the proportion of oil and regardless of the number of coils used 40 to heat the oil, the heating and topping of the oil may be carried on during the period when the water is being withdrawn from the tank after settling, as well as during the period in which the water is settling from 45 the mixture.

Having described a preferred form of my invention, I claim:

1. A process of separating hydrocarbons and water from a mixture thereof, which 50 embodies heating the mixture and maintaining thereon a pressure substantially just slightly greater than the pressure of water vapor at the temperature used, then changing the relation of temperature and pressure 55 to make the pressure greater relatively to the water vapor pressure at such temperature by maintaining the temperature of the upper part of the liquid sufficiently above that of

the remaining part to generate vapors from said upper part of the liquid body, and 60 simultaneously withdrawing some of such vapors while the water is settling out of the mixture by reason of such changed relationship of temperature and pressure.

2. A process of separating hydrocarbons 65 and water from a mixture thereof, which embodies heating the mixture and maintaining thereon a pressure substantially just slightly greater than the pressure of water vapor at the temperature used, then changing 70 the relation of temperature and pressure to make the pressure greater relatively to the water vapor pressure at such temperature by increasing the temperature of the top part of the liquid, and withdrawing some of the 75 vapors generated by said increase in temperature while retaining a sufficient pressure in excess of the water vapor pressure at the particular temperature to cause the water to settle out of the mixture. 80

3. The herein described process of separating hydrocarbons and water from a mixture thereof, embodying first heating the liquids to a point approximately that of the normal boiling point of water, simultaneously 85 withdrawing vapors from the heated liquids and holding them under pressure just sufficient to prevent the liquid from foaming over by reason of vaporization of the water, then heating the upper parts of the liquid 90 only to develop additional pressure upon the liquids without increasing the temperature of the body of the liquids, and simultaneously withdrawing some of the additional vapors produced by said heating and allowing 95 the water to settle out by gravitation.

4. The herein described process of separating and topping hydrocarbons from a water mixture, embodying heating the mixture and simultaneously holding thereon a pressure 100 sufficient to prevent vaporization of the water and thereby inducing the separation of the water from the hydrocarbons; then further heating the hydrocarbons without substantially heating the water to develop 105 vapors from the hydrocarbons and simultaneously holding an increased pressure on the liquid and simultaneously withdrawing some of the vapors as the water settles out of the mixture. 110

In witness that I claim the foregoing I have hereunto subscribed my name this 10th day of February, 1919.

WALTER ARTHUR BROWN.
